(57) **CLAIM**

The ornamental design for a headlight for a vehicle as shown and described.

DESCRIPTION

FIG. 1 is a front view of a headlight for a vehicle according to the design;

FIG. 2 is a right, front perspective view thereof;

FIG. 3 is a left, bottom perspective view thereof;

FIG. 4 is a right side view thereof;

FIG. 5 is a left side view thereof;

FIG. 6 is a top view thereof;

FIG. 7 is a bottom view thereof; and,

FIG. 8 is a rear view thereof.

The broken lines in the drawings indicate a boundary between claimed and unclaimed portions and form no part of the claim. The deemphasized, grayscale portions shown inside the broken line boundaries form no part of the claimed design. The "BMW" forming part of the claimed design is a registered trademark of Bayerische Motoren Werke Aktiengesellschaft.
